(57) **CLAIM**

The ornamental design for a swivel plant hook, as shown and described.

DESCRIPTION

FIG. 1 is a rear and top perspective view of a swivel plant hook, showing my new design;

FIG. 2 is a front and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated in FIG. 2. The dash dot dash lines in FIGS. 2 and 9 are for the purpose of depicting the cut line of the enlarged view and form no part of the claim.
